UNITED STATES PATENT OFFICE.

ALFRED P. LOHMAN, OF AKRON, OHIO.

MIXING AND KNEADING MACHINE AND PROCESS.

1,406,666.

Specification of Letters Patent. Patented Feb. 14, 1922.

Application filed August 16, 1919. Serial No. 317,871.

To all whom it may concern:

Be it known that I, ALFRED P. LOHMAN, a citizen of the United States, and a resident of Akron, in the county of Summit and State of Ohio, have invented certain new and useful Improvements in Mixing and Kneading Machines and Processes, of which the following is a description.

The general object of my invention is to provide for the mixing and kneading of the material in a more thorough, efficient, and uniform manner, with an accompanying reduction in both the power and labor costs and time of operation, as compared with machines and processes now employed for this purpose.

The most commonly used type of machine for mixing materials such as rubber or other gums with the various pigments or other materials with which it is desired to combine them, is the so-called "mixing mill." This mixing mill comprises, in general, two adjacent, parallel cylinders adapted to revolve in opposite angular directions at different peripheral velocities. The material to be mixed is placed into or near the bite of these two cylinders, and by reason of the difference in peripheral velocities, there results a smearing action along the line of contact between the two cylinders which operates to mix more or less intimately the various component materials. However, in these mills the line of smearing contact is limited to the length of the cylinders. Also, there is no effective provision for longitudinal travel of the ingredients, their only longitudinal movement being accomplished by merely the haphazard and occasional manual shifting of portions of the material from one end of the mill to the other by the operator.

Among the specific objects of my invention are, the extension of the line of smearing contact of the mill to effect a more thorough smearing action, and the provision of means for continuously and automatically conveying the ingredients longitudinally substantially from end to end of the machine to effect a more uniform intermingling than has been heretofore possible.

Other objects of my invention will more fully appear from the specification and claims which follow.

In the accompanying drawings,

Fig. 1 is a perspective view of one form of my improved machine.

Fig. 2 is a side elevation thereof, partly broken away.

Figs. 3 and 4 are detail views partly in cross-section, of one form of my material supplying cartridge.

Figs. 5, 6 and 7 are side elevations of three different types of mixing members which I may employ.

Fig. 6^a is a transverse sectional view on the lines 6—6 of Fig. 6.

Figs. 8 and 9 are cross sectional views of the members shown in Figs. 5 and 6, respectively, and Fig. 10 is an end elevation of the member shown in Fig. 7.

Fig. 11 is a side elevation of a still different form of mixing member, and Fig. 12 is a development, on a slightly reduced scale, of the periphery of the member shown in Fig. 11.

Mounted in a suitable frame 11 (Figs. 1 and 2) is the mixing chamber 12. This chamber may be of any desired form, but as here illustrated it is cylindrical.

The mixing member 13 is revolvably mounted within the chamber 12, and may be rotated by any suitable power transmitting means, such as the gear G. The member 13 is provided, as shown more clearly in Figs. 5, 6 and 7, with a plurality of helically arranged blades or flanges. In each instance, 80

the helix of one of the blades, as 14, is right-handed when viewed from the lower or left end of the member 13, and the helix of another blade, such as 15, is left-handed, when so viewed. It will be noted, also, that there is a gap 16 between the right-hand end of the blade 14, and the right-hand end of the blade 15, and a similar gap 17 between the left-hand end of blade 15 and the left-hand end of blade 14.

The result of the above described arrangement of blades is that as the mixing member rotates within the mixing chamber, one of the blades, say blade 14, will convey the material from one (in this case the left-hand) end of the chamber substantially to the opposite end of the chamber, whence the material will pass through the gap 16 and be conveyed by the blade 15, substantially to its starting point. It will

then pass through the gap 17 and repeat the cycle again and again until the batch of material is removed from the machine.

The above described operation serves to commingle the component materials uniformly, but in order to effect a more intimate mixture, I have provided each of the blades 14, 15, with a "smearing" surface, 14^a, 15^b, in addition to its conveying surface 14^a, 15^a. These smearing surfaces may be integral with the blades, as shown, or may be separable, and may be smooth or serrated as found most desirable. As clearly shown in the drawing, the conveying surfaces of the blades are so shaped as to not unduly force the material outwardly against the inner wall or surface of the chamber, their primary function being, by virtue of their helical longitudinal arrangement, to convey the material longitudinally. However, it is obvious that a certain amount of the material will constantly find its way between these smearing surfaces and the inner surface of the chamber. The resulting smearing action takes place over an extended surface by reason of the coaction between smearing surfaces of the long helical blades with the relatively stationary inner surface of the chamber, and as a result of this extended smearing action and the simultaneous longitudinal travel of the material from substantially end to end of the cylinder, the component materials are mixed together with great thoroughness.

As shown in Fig. 6^a, the ends of the blades adjacent the end walls of the mixing chamber may be spiral, with the result that they remove from these walls any material which may have a tendency to adhere thereto and assist in reversing the flow of material in its travel to the opposite end of the cylinder.

Referring particularly to Figs. 1 and 2, the mixing chamber 12 may be heated or cooled by any suitable means, as by a steam or water jacket 19, which surrounds the mixing chamber, and is supplied with steam or water from any suitable source such as the pipes indicated at 20. The interior of the mixing member may be similarly heated or cooled if desired.

Hinged at 21 within the frame 11, is the access door 22 of the mixing chamber. Any suitable means may be employed for hinging this door, but preferably the hinge is so constructed as to leave a blade or interrupter such as 21' within the cylinder. The purpose of the blade is to break up any tendency which may exist for the same material to idly revolve with the rotor during successive rotations thereof. This door 22 when open occupies the position shown in full lines in Fig. 1, and in dotted lines in Fig. 2. A cover 23 may also be provided

and, as here shown, hinged to the frame 11 at 24. Any suitable means may be employed for elevating the door 22, such, for example, as the fluid pressure devices indicated at 25, which are connected to the lower door 22, by a flexible connector 26. Instead of arranging these fluid pressure devices as shown, a single device of this character may be applied to the bottom of the door 22 at its center, to push this door closed. The cover 23 may be opened and closed manually or in any other desired manner.

The door 22 may be provided with means for retaining a drum or similar container for supplying certain ingredients to the materials in the mixing chamber during the mixing operation. For this purpose, I employ the members 27, 28, which are revolvably mounted and capable of limited longitudinal movement in the bosses 29, 30, at opposite ends of the door 22. As indicated in Figs. 1, 3 and 4, the inner ends of these members are screw threaded, and their outer ends are provided with hand wheels or similar devices such as shown at 31, 32, to facilitate their manual manipulation.

A drum which I may use to advantage in this connection comprises a hollow cylindrical shell 33 provided at each end with an end piece or closure 34. A pin 35 formed upon one of the inwardly extending prongs 36 of the end piece co-operates with a U-shaped slot 37 in the end of the shell, to keep the end piece in the desired position. The end piece 34 is provided with a female screw 38 to receive the screw threaded end of the member 28. The end piece for the other end of the drum is like the end piece 34. The female screw 38 in one or both of the end pieces 34 is preferably located off center, so as to give the drum the agitated motion of a tumbling barrel. As shown in Fig. 1, I preferably provide upon the frame 11, an idler pulley 39, which guides a suitably driven chain, with which the sprocket 40, keyed to the member 27, is adapted to cooperate when the door 22 is closed, to rotate the drum 33. Any other desired form of drive, such as friction disks, may be substituted for the chain and sprocket drive here shown.

It may here be pointed out that an important feature of the material supplying means just described is its portability. It may be filled and closed at any desired source of supply and then transported to the mixing machine. It is not again opened until it is within the mixing machine, as will presently appear. This feature is particularly advantageous when the material to be supplied is of a dusty, disagreeable or unhygienic nature and it is desired to guard the operatives from contact with it.

In operation, some of the materials to be mixed are placed in the mixing chamber.

The drum is filled with certain other ingredients such as pigments or other desired material which it is desired to mix with the materials in the mixing chamber, and the 5 end pieces are held in closed position by the pin 35 resting in the inner extremity of the slot 36, as shown in Fig. 4. The drum is then placed in the door 22, the screw threaded ends of the members 27, 28, being screwed 10 into the drum ends 34, as also shown in Fig. 4.

Power is now applied to the gear G, to drive the mixing member 13, and the fluid operated device is actuated to raise the door 15 22. This door may not be completely closed at first due to the interference of a large amount of material in the mixing chamber. However, continued rotation of the mixing member will so readjust the position 20 of the material within the chamber that the lower door will be permitted to close completely. The cover is then closed, and if desired it may be arranged so that when closed, it locks the door 22 in position, as 25 shown in the full lines in Fig. 2. This, however, is not essential, and the cover may be eliminated entirely, without affecting the efficient operation of the mixer.

The sprocket 40 now rotates the drum 33, 30 and as a result of this rotation the shell of the drum is moved circumferentially with respect to the end pieces so that the pin 35 rests in the inner end of the longitudinal portion of the slot 37, as shown at 35', Fig. 35. Whenever it is desired to introduce the material contained in the drum into the mixing chamber, the members 27, 28, are pulled outwardly, thus pulling the end pieces into the position shown in Fig. 3. The gaps thus 40 left between the ends of the shell and the end pieces provide an outlet through which the material is sifted into the mixing chamber as the drum rotates. The tumbling barrel action resulting from the off-center 45 mounting of the drum accelerates the egress of the material therefrom.

The action of the rotating mixing member 13 upon the component materials is as above described. This action may be continued 50 as long as is necessary to effect the desired mixing or kneading of the material. The cover and door of the chamber are then again opened and the mixed material is removed.

55 The modified form of mixing member shown in Fig. 11 is found preferable, under certain circumstances, to any of those above described. In this modified form, I have indicated the blades by the letters A, 60 B, C and D. The blades A and D terminate in end scrapers which may be spirally arranged, as shown, for example, in Fig. 6a. But these two blades are preferably shorter than the corresponding blades 14, 15 of Fig.

6, for example, and the intermediate blades 65 B, C, are provided for extending the longitudinal movement of the material initiated by the blades A, B.

The operation of this modified construction will be more readily understood by referring to Fig. 12, which shows a development of its surface. Let us first trace the movement of the material which we find being conveyed by the blade D. As the member rotates, this material is conveyed from 70 the top of the left-hand end of blade D (top of Fig. 12) to the blade B. Thence it is conveyed to the right, to substantially the right-hand end of the cylinder where it passes through port B D. Passing through 80 this port part of it will go through the smaller port B C onto the blade C, and part through the smaller port C D onto the blade D again.

That portion of the material that has 85 passed through B C will now be conveyed by blade C to substantially the left-hand end of the cylinder where, in passing through the port A C, part will pass through C B onto blade B again and part through A B 90 onto blade A, which will in turn convey it through port C A onto blade C again.

Thus it is apparent that the material is not only moved substantially from end to end of the cylinder and subjected to the 95 effective smearing action heretofore described in connection with the other forms of mixing members, but it is also repeatedly divided and subdivided in a manner which in certain instances adds materially to the effectiveness of the mixing.

It is obvious from the above that no skilled labor is required in the operation of my machine. The exact amount of each of the component materials for each batch to 105 be mixed is, of course, determined in advance. It can also be predetermined how long the mixing operation should be continued before and after the material from the drum is introduced into the chamber. 110 All that the operator has to do is to supply the measured quantities of material, start the machine in motion, open the drum at a predetermined time, and finally stop the machine at another predetermined time and 115 remove the mixed material. In other words, the personal equation is entirely eliminated, and not only is each batch of material mixed to the desired degree of thoroughness, but each batch is exactly like every other 120 batch. Thus a uniformly homogeneous product is obtained.

The terms and expressions which I have employed are used as terms of description and not of limitation, and I have no intention, in the use of such terms and expressions, of excluding any mechanical equivalents of the features shown and described,

or portions thereof, but recognize that various structural modifications are possible within the scope of the invention claimed.

What I claim is:

5 1. The method of mixing and kneading materials which consists in propelling the materials continually and alternately from end to end of a confining space, and simultaneously imparting to the materials movement about the periphery of said space.

10 2. The method of mixing and kneading materials which consists in propelling the materials continually and alternately from end to end of a confining space, and simultaneously imparting to the material a smearing action.

15 3. A device for mixing materials comprising a container and means located therein for propelling the materials continuously and alternately from end to end of said container, and simultaneously imparting to the material movement about the periphery of said container.

20 4. A device for mixing materials comprising a container and means located therein for propelling the materials continuously and alternately from end to end of said container and simultaneously imparting to the material a smearing action between said means and the inner peripheral surface of said container.

25 5. A device for mixing materials comprising a container and means located therein and forming with said container a confined space, said means being constructed and arranged to propel the materials continuously and alternately from end to end of the container within said confined space, and simultaneously to impart to the material movement about the periphery of said container.

30 6. In a machine for mixing and kneading materials, the combination of a substantially cylindrical mixing chamber, and a relatively 45 rotary member located therein, said chamber and member being adapted, by their relative rotation, to propel said materials continuously and alternately from end to end of said chamber and simultaneously to impart to the materials circumferential movement about the inner peripheral surface of said chamber.

35 7. In a machine for mixing and kneading materials, the combination of a substantially cylindrical mixing chamber and a relatively 50 rotary member located therein and comprising an axial body portion provided with a right hand helical flange and a left hand helical flange, said flanges beginning at opposite ends of the chamber and extending substantially to the end opposite that of beginning and extending also throughout their length uninterruptedly from said body portion substantially to the inner cylindrical 55 surface of the chamber, whereby said ma-

terial is conveyed continuously and alternately from end to end of the chamber.

8. In a machine for mixing and kneading materials, the combination of a substantially cylindrical mixing chamber and a relatively 70 rotary member located therein and comprising an axial body portion provided with a right hand helical flange and a left hand helical flange, said flanges beginning at opposite ends of the chamber and extending substantially to the end opposite that of beginning and extending also throughout their length uninterruptedly from said body portion substantially to the inner cylindrical surface of the chamber, whereby said material 75 is conveyed continuously and alternately from end to end of the chamber, said flanges terminating in scrapers for the end walls of the chamber.

9. In a machine for mixing and kneading 80 materials, the combination of a substantially cylindrical mixing chamber and a relatively rotary member located therein and comprising an axial body portion provided with a right hand helical flange and a left hand 85 helical flange, said flanges beginning at opposite ends of the chamber and extending substantially to the end opposite that of beginning and extending also throughout their length uninterruptedly from said body portion substantially to the inner cylindrical 90 surface of the chamber, whereby said material is conveyed continuously and alternately from end to end of the chamber, said body portion being provided also with one 95 or more additional flanges intermediate said first mentioned flanges.

10. In a machine for mixing and kneading materials, the combination of a substantially cylindrical mixing chamber and a relatively 100 rotary member located therein and comprising an axial body portion provided with a right hand helical flange and a left hand 105 helical flange, said flanges beginning at opposite ends of the chamber and extending with substantially a one-half turn substantially to the end opposite that of beginning and extending also throughout their length uninterruptedly from said body portion substantially to the inner cylindrical surface of 110 the chamber, whereby said material is conveyed continuously and alternately from end to end of said chamber.

11. In a machine for mixing and kneading 115 materials, the combination of a substantially cylindrical mixing chamber and a relatively 120 rotary member located therein and comprising an axial body portion provided with a right hand helical flange and a left hand 125 helical flange, said flanges beginning at opposite ends of the chamber and extending substantially to the end opposite that of beginning and extending also throughout their length uninterruptedly from said body portion to the inner cylindrical surface of the 130

chamber, each of said flanges being provided with a conveying surface and with a smearing surface adjacent the inner cylindrical surface of the chamber, whereby said material is conveyed continuously and alternately from end to end of the chamber and simultaneously smeared against said inner surface.

5. materials, a mixing chamber, a swinging door mounted thereon, a feeding device adapted to be mounted on said door when open, and means operable at the will of the operator for causing said device to feed material to said machine when said door is closed.

12. In a machine for mixing and kneading

ALFRED P. LOHmann.
